UNITED STATES PATENT OFFICE.

EMIL G. BOGUSCH, OF DETROIT, MICHIGAN, ASSIGNOR OF ONE-FOURTH TO CHARLES E. WISNER, OF DETROIT, MICHIGAN.

INTERNAL-COMBUSTION ENGINE.

Application filed April 5, 1919. Serial No. 287,771.

To all whom it may concern:

Be it known that I, EMIL G. BOGUSCH, a citizen of the United States, residing at Detroit, county of Wayne, State of Michigan, have invented a certain new and useful Improvement in Internal-Combustion Engines, and declare the following to be a full, clear, and exact description of the same, such as will enable others skilled in the art to which it pertains to make and use the same, reference being had to the accompanying drawings, which form a part of this specification.

This invention relates to internal combustion engines, and its object is to provide a construction whereby oils of low volatility, such as a heavy petroleum, may be utilized in the same manner and with as great efficiency as the present type of engine utilizing a high grade of gasoline. In particular the object of the invention is to provide a fuel inlet adapted to pulverize the fuel as it passes into the combustion chamber and further to provide an engine construction in which the fuel is discharged into the chamber during practically the entire intake stroke of the piston to secure the time element required for pulverization of the fuel and at practically the completion of the stroke to introduce the required amount of air to produce an explosive mixture. A further feature of the invention is in providing the fuel inlet with means operating in conjunction with the throttle valve to vary the fuel flow in relation to the variation in position of the throttle valve. Further features of the invention are involved in the specific construction of the fuel pulverizing device. These and other objects and the several novel features of the invention are hereinafter more fully described and claimed and shown in the accompanying drawings in which—

Fig. 1 is a vertical section of an internal combustion engine embodying my invention.

Fig. 2 is a vertical section of the fuel pulverizing device.

The engine is of the usual four-cycle type, the cylinder 1 being of the usual character provided with a crank case 2 and with a piston 3 and piston rod 4 connected with the usual crank (not here shown). The cylinder is provided at the upper end with the usual spark plug 5 and in the construction here shown is provided with an inlet valve 6 at one side of the cylinder controlling a port 7

opening into a recess 8 that is open to the cylinder above the highest point occupied by the top of the piston on the compression stroke. The inlet 7 is in the manifold 9 which has an opening to atmosphere controlled by an automatic valve 10. Flow through the conduit is also controlled by means of a manually operable throttle valve 11, which may be provided with a lever 12 attached to the stem of the valve and by means of which it may be turned, as indicated by dotted lines in Fig. 1. Fuel is introduced into the chamber 8 through what I have termed a pulverizer 13. This pulverizer consists of a centrally chambered plug 14 threaded for insertion through the upper wall of the chamber 8 and is provided with a valve seat at the lower end for the valve 15, the stem of which extends upward through the central chamber 16 of the plug. A spring 17 is provided engaging a nut 18 or head on the stem of the valve by means of which the valve is normally seated. This chamber 16 is open to atmosphere by means of several conduits 19 which lead into the central chamber as indicated. Vertical conduits 20 are also provided opening into the conduits 19 at the upper end and into the face of the seat for the valve 15. These are air ports and the seating of the valve closes the said ports to the cylinder. Oil is supplied to this chamber by means of the atomizer 21 of small capacity which is in the form of a Venturi tube rotatably mounted in an aperture in the side of the plug. This tube at the point of greatest restriction is provided with a series of apertures 22. Externally of the tube is provided a groove in which rides a collar 23. The collar provides a circumferential channel open to the fuel line 25 by means of a conduit 24 in the collar. The circumferential channel provides fuel for all the apertures 22 in the atomizer. Passage of air through the Venturi tube 21 draws fuel from the tube 25 into the chamber 16 and through the cylinder as hereinafter shown. The source of supply of fuel is not here shown, but it is to be understood that the tube 25 leads thereto, and that the flow of fuel through the tube 25 is controlled by the reduction in pressure in the venturi 21. As before stated, the engine is of the usual four-cycle type except that the main air valve 6 is opened at about completion of the intake stroke instead of at the beginning

thereof as is usual. The valve 15, however, is an automatic valve and on the beginning of the intake stroke of the piston and as soon as the reduction of pressure in the cylinder 5 is sufficient to unseat the valve 15, air and fuel is drawn through the chamber 16 and into the chamber 8 and thence into the cylinder and the flow of fuel from the time of the opening of the valve continues during 10 practically the entire stroke of the piston in order that only a small volume of fuel is drawn in at a single instant of time but, by arranging the engine to operate in the manner stated, the period of time of the inlet 15 of fuel is continued throughout practically the entire stroke in order that the desired quantity may be introduced. The fuel by this arrangement may be very small in volume and is mixed with the air by being 20 drawn into the venturi 21 and is further pulverized in passing across the face of the valve 15 where it comes in contact with the fine streams of air through the conduits 19 and 20. By this arrangement the fuel is introduced into the cylinder in a very finely divided state as distinguished from the condition in which it would be found if the oil were introduced practically in a body. The 25 inlet valve 6 under this condition must be mechanically operated in order that a pressure below atmosphere may be maintained in the cylinder for the proper period of time. Although some air is introduced through the pulverizer it is insufficient to 30 support combustion. Therefore, at about completion of the intake stroke of the piston, the valve 6 is opened and air flows in through the manifold to the extent required by the degree of vacuum in the cylinder at 35 the time of the opening. This final introduction of air provides sufficient oxygen to support combustion and produce an explosive mixture, and an oil of low volatility may be utilized in this engine by reason of 40 the highly pulverized state in which it is introduced into the cylinder.

There are many engines at present which utilize an oil of low volatility but these are usually ignited by reason of a high degree 50 of pressure attained in the compression stroke. This engine, however, is of the ordinary type utilizing the electric spark for ignition and the problem involved is to secure so high a state of pulverization of fuel 55 and mixture of air therewith as to produce an explosive mixture. In practice I have found it most practicable to open the intake valve about thirty degrees before the finish of the stroke and to close at about thirty degrees after the finish of the stroke during 60 which movement of the piston ample time is given for introduction of air through operation of the degree of vacuum. The exhaust port is not here shown, but it is to be understood as being of the usual type preferably 65

mechanically operated. In the usual internal combustion engine a fuel charge rich in percentage of oil is usually required in starting the same, which percentage may be decreased as the engine speed is increased. 70 The flow of oil in my improved engine may be controlled directly by the throttle valve. For this purpose I have provided a lever 26 apertured to pass over the stem of the plug 13 and on which the spring 17 seats as indicated in the drawing. This lever is pivoted at 27 to a convenient standard 28 secured to the engine casting and to the end of this lever is pivotally connected a link 29 which in turn is pivotally connected with a lever 30 secured to the valve stem or forming part of the lever 12. On operation of the lever 12 to open the throttle valve 11 the lever 26 is lowered as indicated by dotted lines in Fig. 1 which releases the companion of the spring 17 requiring a lesser degree of vacuum to open the same than is required when the throttle valve is practically fully open. With a practically closed throttle and spring 17 under greatest compression, the valve 15 opens later than when the throttle is opened and spring pressure reduced. Therefore, when only a small volume of air may be introduced, the amount of oil is reduced and vice versa. 95

From the foregoing description it is evident that this engine, although burning a low grade of fuel oil, is practicable by reason of the high state of pulverization in which the oil is introduced into the cylinder and therefore that a high state of compression to produce an ignition thereof is dispensed with as is also the necessity of feeding the fuel to the cylinder under pressure as has been the practice in some cases heretofore; and that the introduction of fuel is solely by reason of reduction of pressure in the cylinder which is depended upon to provide the necessary quantity of fuel and in the necessary highly pulverized state and also to introduce at the proper time the required amount of air for combustion. Thus the engine is operative in a manner analogous to the well known internal combustion engine utilizing gasoline or fuel oil of high volatility and therefore one whose operation is readily understood by those familiar with the operation of engines of such type. 110

Having thus briefly described my invention, what I claim is—

1. In an internal combustion engine of the four-cycle type including a cylinder and piston operable therein, a fuel inlet adapted to introduce fuel and air in a highly pulverized state during substantially the entire intake stroke of the piston, a spring-controlled valve controlling the said fuel inlet, an air valve adapted to open the cylinder to a flow of air at atmospheric pressure at about the completion of the intake stroke of the pis- 125

ton, a throttle valve controlling the volume of flow of air, and means whereby the opening of the throttle valve decreases the tension of the spring of the fuel valve.

5. 2. In an internal combustion engine of the four-cycle type including a cylinder and piston reciprocable therein, a fuel pulverizing device consisting of a chambered plug, a valve seating in the end of the plug, a spring
10 for the valve, a series of air conduits leading from atmosphere and opening through the seat of the valve, a fuel conduit opening into the chamber of the valve, the construction being such that a flow of fuel is caused by

reduction of pressure within the cylinder, a main air conduit, the cylinder being ported at the upper end to which the air conduit leads, an air valve controlling the port, means for opening the air valve at about the completion of the intake stroke of the cylinder, a throttle valve in the conduit for varying the flow of air therethrough, and means whereby the opening of the throttle valve decreases the tension of the spring for the fuel valve. 15 20 25

In testimony whereof, I sign this specification.

EMIL G. BOGUSCH.
